GUSTAV B. PETSCHE, OF YONKERS, NEW YORK.

ROTARY COMPRESSOR.

1,390,586.

Specification of Letters Patent. Patented Sept. 13, 1921.

Application filed October 28, 1920. Serial No. 420,082.

To all whom it may concern:

Be it known that I, GUSTAV B. PETSCHE, a citizen of the United States of America, and resident of Yonkers, in the county of 5 Westchester, in the State of New York, have invented a certain new and useful Improvement in Rotary Compressors, of which the following is a true and exact description, reference being had to the accompanying drawings, which form a part 10 thereof.

My invention relates to rotary compressors and has for its object to provide for the cooling of the compressed gas delivered 15 from the compressor and for the cooling and re-use of the lubricating oil used in the rotary compressor in large quantity, in a separate oil cooler located at a lower level than the gas cooler, and for the re-use of the 20 cooled oil which can be cooled to such a point that it will absorb a portion of the heat generated by compression and thus lower the temperature of the compressed gases, particularly, though not exclusively, 25 my invention relates to compound rotary compressors having such dimensions that, assuming but two compounded compressors to be used, the secondary compressor will have such capacity and dimensions that it 30 will act upon an equal weight of gas to that acted upon by the first compressor.

My invention has also to do with various details of construction and will be best understood as described in connection with 35 the drawings in which my invention is illustrated in what I believe to be its best and most advantageous form and in which—

Figure 1 is a partly sectional side elevation through one of the compounded compressors taken on the section line 1—1 of Fig. 3.

Fig. 2 is a similar partly sectional elevation of the second compressor taken on the section line 2—2 of Fig. 3, and

Fig. 3 is a sectional side elevation taken as on section line 3—3 of Fig. 1, and

Fig. 4 is a view showing how the two compressors, not formed in the same casting, can be conveniently combined with operative and inter-cooling mechanism.

A and A' are the two compressors formed, as shown in Figs. 1, 2 and 3, in a single casting and provided with face plates A² and A³. The capacities of the two compressors are made such that the second compressor A' will contain and act upon the

same weight of gas as is contained and acted upon by the first compressor A. B and B' indicate the cylindrical interiors of the two compressing cylinders; B² and B³ indicating the points at which the cylindrical surface of the compressor A is cut away to give clearance to the piston extension, b² and b³ indicating two similar clearances provided in the cylinder A'. C and C' indicate bearing surfaces for a swivel block. E is the admission chamber of the compressor A. F the delivery chamber of this compressor. F² is an oil receiving chamber at the bottom of the delivery chamber 70 which should be so formed as to act as an oil separator and which has an oil exit opening F³ at its bottom. E' and F' indicating the admission and delivery chambers of the compressor A'. The chamber E' terminates in an oil well E² into which the upper end of the slide partition J' of the smaller compressor extends. G is the inter-cooler connecting, as shown, with the delivery passage F of the compressor A and 80 with the admission chamber E' of the compressor A'. H is the driving shaft to which are secured the eccentrics H' and H² on which work the eccentric ring pistons indicated at I and I', said pistons being provided with extensions J and J' which, as illustrated, are made in a form of slides working in swivel blocks K and K' seated in the bearings C and C'. As shown the admission to the compressors is through 90 passages J², j² and ports J³, j³ in the respective extensions J and J' a feature of construction covered by my co-pending application filed October 6, 1920, Serial No. 415,145, C² and c² indicate delivery ports 95 formed in the bearing surface C and C' and opening into the delivery chambers F and F'. The port C² as shown, opens into the oil chamber F² at the bottom of chamber F. K² and k² indicate ports formed in the 100 swivel blocks K, K' so formed and proportioned as to enable the swivel blocks to act as valves to open and close the ports C², c² at proper times.

In the modification shown in Fig. 4 AA 105 indicates the larger compressor, AA' the smaller compressor. HH indicates the driving shaft for both compressors and L a motor acting on the driving shaft between the two compressors. GG indicates the inter-cooler.

M is an oil pipe leading from opening F³

of the oil chamber F to an oil cooler made up, as shown, of oil pipes M' passing through a water chamber N. The oil passing from the cooler through pipe M² to the 5 oil well E².

In operation the gas to be compressed enters the compressor A through the chamber E and the passage J² and port J³ which port remains open during the suction cycle of 10 the piston and until the right hand side of the piston is about to leave contact with the periphery of the cylinder at the point B³. At this time it is closed by the passage of 15 the port J³ above the edge of the swivel block and it remains closed until the left hand side of the piston has come in contact with the periphery of the cylinder at B². The delivery of port C² is closed by a swivel block K during the motion of the piston 20 from the beginning of its operative cycle until it reaches the position shown in Fig. 1 after which the further motion of the piston and of the swivel block opens this port and permits the delivery of the gas through 25 the chamber F and inter-cooler G.

The operation of the compressor A' is, as shown, precisely similar to that of the compressor A but the capacity of the cylinder A' is so reduced that the amount of compressed gas upon which it acts during each 30 cycle will be equal in weight to the gas acted on by the cylinder A and the gas having been deprived of its heat of compression by passing through the inter-cooler the compounded compressors will work with the 35 highest degree of efficiency.

Oil in considerable quantity is fed into the admission chamber E and enters the first compressor with the gas and fills the clearance spaces of the compressor. The oil is forced out of the port C² into the oil well F² and passes through pipe M and cooler M' N to pipe M² by which it is delivered into oil well E² and thence it passes through the 40 admission port j², j³ in slide J' into the smaller compressor being, of course, forced out of delivery port c² into the receiver F' where it can be separated from the gas and recooled again for reuse.

The gas inter-cooler may be of any kind or construction and cooling of the gas, of course, occurs by radiation or conduction from the compressors and is greatly aided by the use of oil in considerable quantity 5 where my means are employed for cooling the oil before reuse in a separate cooler in which the oil can be cooled to a low temperature and which avoids the impairment of the efficiency of the gas cooler which re-

sults from keeping its cooling pipes more 60 or less covered by oil.

Having now described my invention, what I claim as new and desire to secure by Letters Patent, is:

1. A compound compressor comprising a 65 rotary compressor in combination with a second rotary compressor connected to receive and act upon the compressed gas from the first compressor and of such smaller capacity as will receive a substantially equal 70 weight of gas, an intercooler for cooling the compressed gas from the first compressor before its entrance into the second compressor, an oil receiving chamber at the delivery port of the larger compressor, a separate oil cooler connected to said chamber and located at a lower level than the gas cooler and a conduit leading from said cooler to the admission side of the smaller 75 compressor.

2. A compound compressor comprising a 80 rotary compressor in combination with a second rotary compressor connected to receive and act upon the compressed gas from the first compressor and of such smaller 85 capacity as will receive a substantially equal weight of gas, an intercooler for cooling the compressed gas from the first compressor before its entrance into the second compressor, an oil receiving chamber at the delivery port of the larger compressor, a separate oil cooler connected to said chamber and located at a lower level than the gas cooler and a conduit leading from said 90 cooler to the admission port of the smaller 95 compressor.

3. A compound compressor comprising a 100 rotary compressor in combination with a second rotary compressor connected to receive and act upon the compressed gas from the first compressor and of such smaller 105 capacity as will receive a substantially equal weight of gas in compressed condition, said second compressor having a piston extension forming a partition between the admission and exhaust ports and an admission port formed in said extension, an inter-cooler for cooling the gas from the first compressor, having an oil well into which the ported upper end of the piston extension of the second compressor extends, an oil receiving chamber at the delivery port of the larger compressor, a separate oil cooler connected to said chamber and located at a lower level than the gas cooler and a 115 conduit leading from said cooler to the oil well in the gas intercooler.

GUSTAV B. PETSCHE.
